EXPANSIBLE CARTON AND DETACHABLE COVER

Richard E. Paige, New York, N. Y.

Application April 17, 1948, Serial No. 21,640

2 Claims. (Cl. 229—34)

1
My invention relates to improvements in receptacles; especially receptacles for both shipping and displaying merchandise.

The receptacle of this invention is preferably made of flexible sheet material to enable it to be packed or stored in a collapsed state. An important object is to provide a receptacle of such construction that it can be distended or expanded when the contents thereof are to be exhibited; so as to increase the interior space ordinarily enclosed thereby and allow the merchandise therein to be more plainly seen and more easily removed by the purchaser.

A further object is to provide a receptacle with adjustable sides that can be swung outward to a predetermined extent, so as to permit the articles in the receptacle to become separated in some degree, instead of being retained in a compact array or group. In that condition, the articles which, for example, have the form of small individual packages, appear to better advantage and are more quickly sold, because a buyer may hesitate to disturb a well ordered arrangement, but will feel completely at liberty to pick out something from a more or less tumbled pile or heap.

Another object is to provide a receptacle adapted to serve for both shipping the merchandise and exposing it for sale in a shop or store; so that the merchant must necessarily use the box in which the articles are received by him when he offers the contents to his customers.

A still further object is to provide a box or receptacle comprising a body that incorporates all of the necessary features for expanding the body when it is opened, independent of the cover, which can thus be reserved and utilized solely as a sign or panel for such advertising matter as may be needed.

An additional object is to provide a receptacle of the kind indicated, with some of the sides so mounted and connected that they can be swung outward as required, but having parts attached to the sides to limit the outward movement and maintain the sides in their final adjusted positions.

The nature of the improvement is fully set forth in the ensuing description, and the novel characteristics are defined in the claims. The structure illustrated is by no means the only one in which the invention can be embodied, and I reserve the right to make changes in details without departing from the main design in which the invention and the controlling principle there-of are contained.

2
On the drawings:

Figure 1 is a developed view of a blank of sheet material cut and creased so that it can be set up in the form desired.

Figure 2 is a similar view showing the blank partly folded and shaped.

Figure 3 is a transverse section along line 3—3 of Figure 2.

Figure 4 is a top plan of the finished receptacle.

Figure 5 is a transverse section on the line 5—5 of Figure 4.

Figure 6 is a longitudinal section on the line 6—6 of Figure 4.

Figure 7 is a plan view of a panel adapted to serve as a cover for the receptacle.

Figure 8 is a view, partly in section, showing how the cover or lid is attached to the body of the receptacle.

Figure 9 is a perspective view showing the receptacle in its completed state with a number of packages therein and the lid or cover turned up to expose the contents to view; and

Figure 10 is a section on the line 10—10 of Figure 9.

25 The blank out of which the receptacle is made, as shown in Figures 1 and 2 is of sheet material such as cardboard or the like, comprising a panel 1 to serve as the bottom, and elongated parts 2 to make the ends connected to opposite edges of the panel 1 along transverse creases or score lines 3. Attached to the panel 1 along opposite edges are additional parts 4 which make the sides of the receptacle when it is set up, the parts 4 joined to the panel 1 along creases or score lines 5. The receptacle is preferably rectangular, but the invention is not necessarily limited to such configuration.

Each of the extremities of the parts 4 carries a hinged flap 6. These flaps have terminal projections 7 which are triangular, and connecting webs 8 between the projections 7 and the parts 4. The projections 7 and webs 8 are united to each other along creases or score lines 9; and the webs 8 are united to the extremities of the parts 4 along creases or score lines 10. The lines 9 and 10 converge and intersect with the score lines 3 and 5 at the corners of the bottom panel 1. Thus the webs 8 also are triangular in form with the apex of each on the adjacent corner of the bottom 1, and the projections 7 are all triangular but with the apex of each at the outer end of one of the score lines 9. The flaps 6 are separated from the parts 2 along lines 11 which are cut through the material from the outer pointed ends 55 of the projections 7 to the score lines 3.

The parts 2 have transverse score lines 12 and 13 which divide these parts into sections 14, 15 and 16. When the blank is manipulated to set up the box or receptacle, the parts 4 are bent upward into the position shown in Figures 2 and 3, and the flaps 6 are turned around the score lines 10 and brought into overlapping position across the blank along the line 3. The parts 2 are then bent around the lines 3, 12 and 13, so as to fold up the sections 15 against the outer faces of the flaps 6; and the sections 16 down against the inner faces of the overlapping flaps 6. The terminal sections 14 of the parts 2 are then laid flat on the bottom panel 1. These sections are wide enough to press against the sides 4 and hold the ends of the box in place, with the flaps 6 between the sections 15 and 16, as shown in Figure 6. In normal position, the edges 11 of the flaps 6 make contact with the bottom 1. See Figures 5 and 8. The body of the receptacle then has the bottom 1, with sides and ends in upright positions. The top edges of the projections 7 slope downward.

The parts 14 lying flat on the bottom are an important feature of the invention because these parts abut each other as shown on Figure 4 and fit tightly in the box so as to hold the parts 15 over the projections 7 and webs 8.

With the receptacle shaped as described, the body of the receptacle can be expanded as indicated in Figures 9 and 10. When the receptacle is first filled the whole extent of each flap 6 is housed between the sections 15 and 16 of the ends; but the sides 4 can be pulled out slightly by turning them around the lines 5 till the webs 8 are entirely exposed. When the sides 4 have been swung out to this extent, the top edges of the projections 7 are stopped at the junction of the sections 15 and 16 of the ends; and the lower edges are elevated above the bottom 1 of the box as indicated in Figure 10. The outward movement of the sides 4 is thus limited by the projections 7, because these can be now lifted no higher, but the size of the receptacle is increased, making the contents of the package more accessible and easier to grasp and take out.

This result is obtained independently of any cover and the receptacle may be used without a cover in the manner set forth. Further, a cover can be provided as indicated in Figures 7 to 10 inclusive. For this purpose a blank of material is given the form shown in Figure 7, including a central panel 17, and flaps 18 secured thereto along all sides but one and capable of being folded about creases or score lines 19. On the remaining side are two flaps 20 separated by a recess 21 having an enlarged inner end 22. This inner end is somewhat square in shape and at the inner corners are diagonal lines 23 which are cut through the panel 17. The outer end of the recess has diverging sides 24. To attach the cover the section 16 at one end of the box has two cuts 25 beginning at the score line 12 and extending toward each other as indicated at 26. When the flap 18 is in position the ends 26 of the cuts 25 are uppermost, as indicated in Figures 8, 9 and 10. The flaps 20 of the cover are pushed into the box against the section 16 and the adjacent extremities of these flaps are inserted into the cuts 25 so that the shoulders 27 at the sides of the recess 21 where the diverging edges 24 join to the larger inner end 22 of the recess 21, serve as stops so that the cover cannot be pulled out. When the sides 4 are not distended the cover will close the box when it is turned down, so that the

flaps 18 are inserted within the sides 4 and ends of the receptacle.

The width of the flaps 20 is less than the height of the sides of the box, and the distance of the shoulders 27 from the inner end 22 of the recess 21 is about equal to the distance between the upper ends of the parts 26 of the cuts 25 and the top edge of the box. When the cover is folded down to close the box it is pulled up until the shoulders 27 engage the side of the box at the adjacent ends of the cuts 26 as shown in Figure 8. The cover can then be bent along a line crossing the inner end 22 of the recess 21 and can be folded down to closing position. When the cover is to be lifted the flaps 20 are forced downward until the inner end 22 of the recess 21 is in line with the adjacent ends of the cuts 26 as shown on the Figures 9 and 10. The cover then rests against the inside of the box and remains upright.

The contents of the box are indicated as consisting of packages 28 which will ordinarily be in a compact group. When the cover is lifted over and the sides 4 are swung out the packages 28 can be separated more or less and more easily handled for examination and removal.

Having described my invention, what I claim as new is:

1. A receptacle comprising a body having sides and a bottom, and overlapping means connected to the extremities of some of the sides to permit the same to be swung outward and retained in distended position to increase the space for merchandise within the receptacle, the body also having a detachable cover with flaps along one edge; said flaps having a recess between their adjacent ends, the recess having an enlarged inner end with shoulders at the sides, one side of the box having angular cuts below its top edge to receive the adjacent ends of said flaps and connect the cover to the box, with the said flaps being less than the height of said sides and the distance between the shoulders and the inner end of the recess being substantially equal to the distance between the top of the side and the adjacent ends of said cuts.

2. A receptacle having parts to make a body with sides and bottom, some of the sides having hinged connection with the bottom to be swung outward to increase the cubic volume of the interior of the receptacle, flaps comprising webs of inverted triangular form with hinged connection each along one edge to the extremities of said sides, the apex of each web being at the adjacent corner of the bottom, the flaps also having triangular terminal projections hinged to the other edges of said webs, said projections having sloping upper edges, said flaps at the adjacent extremities of said sides extending toward each other and overlapping, said body comprising additional sides which have sections overlying the flaps respectively when the parts are in normal position, the sections also having parts folded over the flaps against the bottom of the box and held in position by free frictional engagement with the inside of the receptacle, the hinged sides being adapted to be swung out to pull the webs clear of said sections, the upper sloping edges of said projections then being engaged by said folded sections to limit the outward movement of said sides, the body also having a detachable cover with flaps along one edge, said flaps having a recess between their adjacent ends, the recess having an enlarged inner end with shoulders at the sides, one side

5

of the box having angular cuts below its upper edge to receive the adjacent ends of said flaps and connect the cover to the box, the width of said flaps on the cover being less than the height of the sides and the distance between the shoulders and the inner end of the recess being substantially equal to the space between the upper edge of the side and the adjacent ends of said cuts.
